FOREIGN PATENT DOCUMENTS

CA 2885399 A1 9/2016

Primary Examiner — Mark A Goodwin(57) **CLAIM**

The ornamental design for a compact track loader, as shown and described.

DESCRIPTION

FIG. 1 is a perspective view of a compact track loader showing our new design.

FIG. 2 is a left side view thereof.

FIG. 3 is a right side view thereof.

FIG. 4 is a front view thereof.

FIG. 5 is a rear view thereof.

FIG. 6 is a top view thereof; and,

FIG. 7 is a bottom view thereof.

The broken line representations of environmental structure in FIGS. 1-7 is for illustrative purposes only and forms no part of the claimed design.

1 Claim, 7 Drawing Sheets(56)
